SOUND RECORDING SYSTEM

Cecil N. Batsel, North Hollywood, Calif., assignor
to Radio Corporation of America, a corporation
of Delaware

Application October 20, 1939, Serial No. 300,401

9 Claims. (Cl. 179—100.3)

This invention relates to sound apparatus and particularly to a sound film recording system whereby greater flexibility of recording and better reproduction of the records made with the system are obtainable.

The invention is particularly related to the variable area type of sound recording whereby a trace or traces longitudinally of the film sound track area separate a varying width opaque portion from a varying width transparent portion, the transverse variations of the trace varying linearly with the amplitude of the signal being recorded. This linear relationship is desirable to accurately record and reproduce the sound source without distortion. However, it is well known that the sound track area of a film is of limited width and that frequently the signal peaks are higher than the upper limit of the film. In such instances the peaks are cut off, producing square-topped areas between the point where the signal went beyond the film width and again returned thereto, and thus introducing a large amount of distortion.

In recording practice, an operator attempts to control the signal level in the electrical transmission circuit between the microphone and light modulator. He attempts to bring the high peak levels within the film range by reducing the gain or increasing the attenuation in the electrical circuit. This operation is, of course, beneficial but it is frequently difficult for the operator to determine the exact point at which the level will go beyond the film width. Furthermore, the change in gain of the circuit introduces varying amounts of distortion and sometimes eliminates or at least reduces the dramatic effect intended.

It has also been found, in the reproduction of signals in theatres, that the average level of theatre reproduction is 15 or 20 db. greater than the original level, particularly in the case of dialogue recording. At normal speech loudness, that is, the level at which speech is naturally heard without artificial aid, considerable volume latitude is permissible without annoyance. When this average speech is reproduced some 20 db. higher without compression of momentary peaks, the loudness at these points causes extreme annoyance to the listener. This condition is found even when the average reproduced value is no greater than necessary for good intelligibility. Poor reproducer frequency characteristics or high theatre reverberation serve to heighten this effect. These energy peaks are not necessarily expressive dynamics used by the actor, but may be caused by lack of breath control or other vocal

defects and the less-trained the actor the more noticeable the defect. However, the dynamics of even the well trained are uncomfortably exaggerated when reproduced at theatre loudness.

It is well known in the art that electronic compressors have been used to control the sound level in the electrical transmission circuit between the microphone and sound recorder, the high energy peaks being automatically brought within the film range. This, of course, requires additional electrical circuits in which distortion may occur, while the compression is generally effective over a considerable range of the signal, necessitating in many cases the use of expanders to reconvert the signal to normal. Such a system is disclosed in U. S. Patent 2,136,723 of November 15, 1938. Curved recording apertures to produce general compression, as shown in U. S. Patent 1,767,790 of June 24, 1930, have also been employed, this type of system also requiring expansion reconversion circuits to bring the signal to normal. The present invention, therefore, is directed to a simple arrangement of a recording aperture whereby the necessary expressive dynamics are brought within the film range with intelligibility and without destroying the linearity of the signal over the major portion of the film range, while the record made with the invention is reproducible with the normal reproducing system.

The principal object of the invention, therefore, is to improve the variable area type of sound recording.

Another object of the invention is to record sound in a variable area type of sound record over a wide range of levels without loss of the expressive dynamics of the original signal.

A further object of the invention is to increase the film amplitude range of the sound track area of a film without disturbing the normal recording or reproducing circuits.

A further object of the invention is to compress a range of 8 db. into a film width range of 2 db. without any substantial loss in intelligibility when normally reproduced.

Although the novel features which are believed to be characteristic of this invention are pointed out with particularity in the claims appended herewith, the manner of its organization and the mode of its operation will be better understood by referring to the following description read in conjunction with the accompanying drawing forming a part thereof, in which

Fig. 1 is a diagrammatic view of a variable area sound recording system embodying the invention;

Fig. 2 is an elevational view of the aperture mask employed in Fig. 1;

Fig. 3 is a view showing the specific details of the mask of Fig. 2; and

Fig. 4 is a graph showing what occurs to a signal recorded with the system of Fig. 1.

Referring now to Fig. 1, light from a constant light source 5 is collected by a lens 6 and projected to an aperture mask 7 having apertures 8 and 9 therein. The light passing through the apertures 8 and 9 is controlled by a pair of shutters 11 operated by an electromagnetic coil 12 connected to a noise reduction unit 4 over conductors 3.

The light beams passing the apertures 8 and 9 and the shutters 11 are projected by a lens 14 on a galvanometer mirror 15 actuated by an electro-magnet 16 connected to an amplifier 2 over conductors 13, which, in turn, is connected to a signal source 10 through amplifier 1. The reflected light from the mirror 15 is projected to a slit mask 17 having a slit 18 therein, the light beams being shown on the mask 17 as shaded portions 19 at times of no signal. The light passing to slit 18 is projected by objective lenses 21 to the sound track portion 22 of a film 23. This sound recording system just described is similar to the well known variable area sound recording system as disclosed in Patents 2,102,776, 2,102,777 and 2,102,778.

Referring now to Fig. 2, the general arrangement of the mask 7 is shown wherein the apertures 8 and 9 are shown in detail as having straight portions 25 and curved portions 26 and 27. For the details of the curved and linear portions of the apertures, reference is made to Fig. 3 wherein the slit 18 is shown with respect to the straight portion 25 and curved portions 26 and 27 of aperture 8, for example. Only one aperture is illustrated in Fig. 3 since the other aperture has identical dimensions, the two apertures producing the well known standard duplex track.

Assuming the slit 18 has a definite length representing the full-track recording width, it is to be noted that the straight section 25 is at an angle of 26° and 34' with respect to the slit and crosses the slit at its center. It will also be noted that the curved ends are drawn on a radius of .093 inch. Thus the light beam may be vibrated or oscillated normal to the slit the distance from the center line of the slit to the extreme ends of the curves, which distance, shown in the practical example is .1094 inch. Thus linear modulation occurs over a light beam movement of .0428 inch, while the compression portion represented by the curves 26 and 27 permits a light beam movement of another .0666 inch, these dimensions being preferable for the usual optical arrangement of standard variable area recording systems.

Considering this particular aperture from the track width standpoint, the linear modulation exists over 80% of the track width which corresponds, from the signal amplitude standpoint, to 80% of normal full-track modulation. In other language, the last 2 db. of the film track width will now accommodate 8 db. of signal level, an overload of 6 db. plus the last 2 db. of track width being compressed into the upper 2 db. of film track range. Thus, the points x represent where the full-track width and the signal level would normally correspond for a linear relationship between the signal and the record. This relationship, however, still exists to points z or 75

80% of the normal film range. However, with the particular curvature shown, the last 2 db. of film track range will now accommodate a 6 db. increase in signal level beyond normal linearity 5 which would correspond to a track width extending to the points y, as shown by the extensions of the straight portion 25. To bring about this relationship, it was found necessary to make the distance b, which is the distance between the points x, substantially equal to the distance a+a', as shown in Fig. 3, this amount of compression being particularly suitable to prevent listener annoyance at theatre levels and obtain the flexibility of recording mentioned above. It also permits reproduction of the record without expansion as will now be explained.

To illustrate exactly what occurs to a signal being recorded with the system of Fig. 1, reference is made to Fig. 4, wherein two cycles of a sine wave are shown, the first cycle 30 having an amplitude which normally would come just within the upper limit of the sound track area as shown at 31. Because of the curvatures 26 and 27 of the slit, the peak of cycle 30 or other waves of this amplitude will be slightly flattened, as shown by the dot-and-dash line 36, this amount of flattening being insufficient to effect intelligibility. Furthermore, the major portion of any recorded signal lies below the line 35 so that very 30 little of the signal will suffer any distortion whatsoever.

Now, referring to the second cycle, it will be seen that this cycle has an amplitude which would normally extend considerably beyond the film width, as shown by the dotted line 32 and which might represent pistol shots or dialogue dramatics. By the invention, this peak is brought within the film range by flattening the peak as shown by the broken line 33 between the lines 31 and 35. If the cycle were recorded normally, the top of the peak would appear as shown by the flat top 34, which destroys intelligibility to a much greater extent than the shape 33. Furthermore, the wave form 33 is reproducible at a 15 or 20 db. greater level without appreciable annoyance whatsoever as compared to the square-topped wave 34. Thus, by the application of applicant's particularly curved aperture, as illustrated, he has retained the desirable linear relationship between signal variation and light variation over the major portion of the film track range and signal variations, and has brought substantially the entire range of energy levels of the signal within the film width in a manner to reduce annoyance and improve the general overall efficiency and quality of the system. He has permitted the sound recording operator a greater latitude, produced a more flexible system, minimized the defects of a signal source, and permits reproduction of the record with the normal reproducing system.

Although one specific aperture has been described above, it is to be understood that for other types of signals, other aperture forms may be preferable.

I claim as my invention:

1. A sound recording system comprising a light source, means for forming light from said source into a beam of a predetermined shape, means for passing a portion of said beam to a film, and means for varying the amount of said portion of said beam passed to said film in accordance with sound waves to be recorded, said light beam forming means providing a linear relationship between the amplitude of said sound waves and

the amount of said beam passing to said film over a range of signal amplitudes of said sound waves corresponding to 80% of the film range and a non-linear relationship between the amplitude of said sound waves and the amount of said beam passing to said film over a higher range of amplitudes of said sound waves, said higher range of amplitudes being recorded in the remaining 20% of film range.

2. A sound recording system comprising a light source, means for projecting light from said source to a film, said film having a predetermined width of sound track area, an aperture for forming said beam into a substantially triangular shape, and means for vibrating said beam in accordance with sound waves to be recorded, the position of said beam determining the amount of light passing to said film, said beam having one side thereof with a straight portion to pass light to said film in direct proportion to the amplitude variations of said sound waves and with a curved portion to increasingly decrease the light to said film per unit increase in amplitude of said sound waves, said straight portion of said triangular beam corresponding to substantially 80% of said predetermined width of the sound track area of said film.

3. A sound recording system comprising a light source, a film, means for forming a slit, and means for projecting certain amounts of said light to the sound track area of said film through said slit in accordance with the amplitude of sound waves to be recorded, said means including a mask having a substantially triangular aperture, one side of said aperture having a straight portion corresponding to substantially 80% of said sound track area width, and a curved portion corresponding to the remaining 20% of said sound track area width.

4. A sound recording system in accordance with claim 3 in which the straight portion of said aperture lies at an angle of substantially $26^{\circ}34'$ with respect to said slit.

5. A sound recording system in accordance with claim 3 in which the curved portion of said aperture is tangent to said straight portion and has a radius of substantially .093 inch.

10 6. A light beam defining aperture mask for a sound recording system comprising a substantially triangular aperture having two straight sides and one side partially straight and partially curved, the curved portion being tangent to said partially straight portion and having a radius of substantially .093 inch.

15 7. The method of sound recording comprising linearly varying the amount of light reaching substantially 80% of the sound track recording area of a film in accordance with the amplitude of sound waves to be recorded and continuously decreasing the variations in light reaching the film with increasing sound wave amplitudes over the remaining 20% of said sound track area.

20 8. The method of sound film recording which comprises compressing into substantially the upper 2 db. range of the sound track, 8 db. of the signal range, 6 db. of said 8 db. normally lying beyond the upper sound track limit, and linearly recording over the remaining range of said sound track extending to the lower limit of the film range.

25 9. The method of sound film recording within a width of sound track area approximating a 30 db. range which comprises compressing into substantially the upper 2 db. range of said sound track width, 8 db. of the signal range, and linearly recording over the remaining range of said sound track width.
